UNITED STATES PATENT OFFICE.

HARRY J. ERNST, OF CINCINNATI, OHIO, ASSIGNOR TO THE D. T. WILLIAMS VALVE COMPANY, OF CINCINNATI, OHIO, A CORPORATION OF OHIO.

VALVE-CONTROLLED FILLING NOZZLE.

Application filed November 27, 1926. Serial No. 151,234.

This invention relates to valve controlled filling devices of the type adapted for use at gasoline filling stations and the like, and has for an object the provision of a balanced and simply operated device.

Another object is to provide a device of this kind having a convenient handle member which serves to facilitate handling of the device, and which also serves as a guard for precluding accidental actuation of the valve.

Another object is to provide a device for the purpose stated which is controllable with one hand, and in which the handle co-operates with the hand of the operator in exercising a fine control of the valve.

These and other objects are attained by the means described herein and disclosed in the accompanying drawing, in which:

20 The figure is a side elevational view of a device of the invention, the part being shown in cross section. The device comprises a hollow casing body 5 provided at its one end 6 with a threaded connecting coupling 7. The coupling 7 carries an open web or spider 8 having a centrally perforated sleeve 9 in which one end 10 of a valve stem 11 is slidably retained. The opposite end 12 of the valve stem 11 is reciprocally retained in a spud or suitably packed bonnet structure 13. The bonnet 13 is screw threaded into a threaded perforation 14 in the end of casing 5 opposite the coupling end 7. Interiorly of the casing 5 is provided a valve seat 15 controlled by a valve 16 mounted on stem 11 and normally retained in a closed position upon seat 15 by a spring member 17 which surrounds stem 11 and has its opposed ends in abutment with the valve and the web 8. From the foregoing it will be apparent that the casing 5 is divided by the valve 16 into a pair of chambers 18 and 19. The chamber 18 communicates with a suitable pipe or flexible hose through which liquid may flow from a tank into the chamber 18. The chamber 19 is provided with a suitable filling spout 20 for insertion into a container to be filled and which directs the liquid which flows from chamber 18 through chamber 19 when the valve is raised from its seat.

In order to provide convenient means for handling the device and for actuating the valve, the casing 5 is provided with a pref-

erably integral handle and actuating support structure which joins the casing 5 at its one end at a point 21 adjacent the coupling end 7 of the device and which point is most remote from the filling spout 20. The handle and guard member 22 is suitably curved to fit the hand and is amply spaced from the side and top end of the casing to permit free movement of the finger of an operator between the handle and casing. At its top the handle 22 is developed into a substantially straight portion 23 which extends in spaced relation across the top of the casing, stem and packing gland. The remaining section 24 of the handle and guard member connects the section 23 with the top portion of the casing adjacent the filling spout 20. From the foregoing, and by reference to the drawings, it will be apparent that the handle and guard member extends in substantially the same plane as the axis of the filling spout, thereby facilitating directional movement and manipulation of the device. A pair of integral arms 25 and 26 extend in spaced relation to one another and from the top portion of the casing 5 to the handle and guard member. A bell crank lever having arms 27 and 28 is pivotally mounted between the arms 25 and 26 adjacent the handle member. The arm 28 lies immediately beneath the section 23 of the handle and guard member and is provided with a flat face 29 against which the end of the valve stem 12 abuts. The arm 27 of the bell crank lever is extended to provide an actuating lever 30. The spring 17 which normally retains the valve 16 upon its seat, also serves to normally retain the bell crank lever in the position shown.

When it is desired to use the filling nozzle the device is grasped in a natural manner with the handle 22 against the palm of the hand and the fingers between the lever 30 and the casing 5. The filling spout may then be conveniently inserted into the filling opening of a tank or container, after which the lever 30 is moved toward the handle 22 by the fingers of the operator. This movement results in a downward movement of the arm 28, which depresses the valve stem 16 against the resistance of the spring 17 and unseats the valve for permitting a flow of fluid from the chamber 18, through the chamber 19 and spout 20. When it is desired to shut off the flow the pressure of 110

the fingers is released from the lever, whereupon the spring closes the valve and also returns the lever to the position shown. It will also be noted that the valve may be retained in a partially open position by imparting a slight movement to the lever. The handle and guard portion 22, 23 and 24 amply protect the actuating lever as well as the protruding portion of the valve stem against accidental operation, and also serves as a mounting means for the actuating bell crank lever.

What is claimed is:

1. In a device of the class described the combination of a valve casing, a valve controlling passage of liquid through the casing, a valve stem having an end projecting through the casing, a handle comprising a continuous member connected at its opposite ends to opposite ends of the casing, and a bell crank lever pivotally mounted on the handle and comprising a pair of arms, one arm lying between the handle member and the valve casing adapted to be actuated toward the said handle member for effecting depression of the valve stem by the other arm.

2. In a device of the class described the combination of a valve casing, a reciprocating valve stem extending through the casing and having one end projecting exteriorly of the casing, a combined guard and handle member connected at its opposite ends to the casing and having its intermediate portion spaced from the casing and the projecting end of the stem, an actuating lever pivotally mounted on the intermediate portion of the handle lying between the said handle and the valve casing and movable in a plane therewith for depressing the valve stem when the lever is moved toward the handle, and resilient means normally retaining the stem in a projected position whereby the lever is yieldingly retained away from the handle.

3. In a valve controlled filling nozzle the combination of a valve casing, a discharge spout and a rigid handle member disposed in a common plane on opposite sides of said

casing, a valve in the casing controlling passage of liquid through the casing, and an actuating lever pivotally mounted on the handle member and lying intermediate the said handle member and valve casing for controlling the valve.

4. In a device of the class described the combination of a casing, a combined handle and protective guard member extending about one side and one end of the casing and connected to the casing at opposite ends thereof, a discharge spout extending angularly from the casing in a plane with the handle member and the casing, a reciprocating valve and stem therefor, one end of the stem projecting through the casing, actuating means pivotally mounted on the handle and guard member and comprising a bell crank lever having an arm normally abutting the end of the valve stem, and an actuating arm normally disposed adjacent the casing, the handle and actuating arm being adapted to be simultaneously grasped by the hand of an operator, whereby the operator may press the actuating arm toward the handle for depressing the valve stem, and resilient means for returning the actuating means and valve stem to their normal positions.

5. In a device of the class described the combination of a casing having an inlet port and a discharge spout, the discharge spout being intermediate the ends of the casing and extending at an angle to the casing, a valve intermediate the inlet port and discharge spout for controlling the flow through the casing, a valve stem extending beyond the casing, a combined protective guard and handle member having its ends secured to the casing and its body portion spaced from the casing, and a lever pivotally carried by the protective guard and handle member and disposed between the casing and body portion of the handle member for depressing the valve stem.

In testimony whereof, I have hereunto subscribed my name this 22nd day of November, 1926.

HARRY J. ERNST.
